UNITED STATES PATENT OFFICE.

HERBERT H. BUFFUM, OF THE WEIRS, NEW HAMPSHIRE.

SPRING STRUCTURE.

1,158,026.

Specification of Letters Patent.

Patented Oct. 26, 1915.

Application filed June 10, 1914. Serial No. 844,204.

To all whom it may concern:

Be it known that I, HERBERT H. BUFFUM, a citizen of the United States, and resident of The Weirs, in the county of Belknap and State of New Hampshire, have invented certain new and useful Improvements in Spring Structures, of which the following is a specification.

This invention relates to vehicle springs and particularly to laminated leaf springs having their outer ends attached to the wheel axles and their inner portions anchored on the vehicle frame. Ordinarily such springs are tapered at both ends and have two points of support on the frame. They have come to be known generally as "cantaliver" springs, although sometimes existing simply as a quarter-elliptic spring provided with a single anchorage on the frame.

My invention has for its object to divide springs of this general character into serially-acting sections, the inner section being held under permanent initial deflection and remaining inactive under the lighter loads or impacts, while the outer section is free to respond to these lighter loads and acts upon the inner section to impart thereto a further deflection under the heavier loads or impacts. To this end I provide the spring with an additional point of support or abutment on the vehicle frame, located between the axle and the main point of anchorage or upward pressure of said spring on the frame, and acting in the manner stated.

The accompanying drawings show various forms and adaptations of the invention, which forms and adaptations are illustrated to facilitate an understanding and not to limit the invention.

On the drawings:—Figure 1 represents a top plan view of a portion of a vehicle equipped with double cantaliver laminated leaf-spring structures embodying one form of the invention. Fig. 2 represents an elevation, partly in section, of the structure included within the range of line 2—2 of Fig. 1. Fig. 3 represents an elevation of the structure included within the range of line 3—3 of Fig. 1. Fig. 4 represents a vertical section through the structure intersected by line 4—4 of Fig. 3. Fig. 5 represents a vertical section through the structure intersected by line 5—5 of Fig. 3. Fig. 6 represents an elevation, partly in section, of details adjacent line 6—6 of Fig. 3. Fig. 7 represents an elevation, as viewed from left to right,

of spring coupling device shown at the extreme left of Fig. 2. Fig. 8 represents an elevation of a single cantaliver spring structure embodying the invention. Fig. 9 represents a vertical section of the structure intersected by line 9—9 of Fig. 8.

The same reference characters indicate the same parts wherever they occur.

Referring to Figs. 1 to 7, which relate to one form of the invention as applied to a vehicle, wheel axles are indicated at 10 and 11 respectively and two of the wheels are indicated at 12, 12. Although Fig. 1 shows only portions of two wheels, it is to be understood that this vehicle structure is intended to include four wheels. A steering knuckle of suitable structure and arrangement is indicated at 13.

Fig. 1 includes a load-sustaining frame which comprises longitudinal members 14, 14, and a series of transverse members 15, the members 14 and 15 being rigid with relation to each other. This frame is supported by springs 16 and 16' at one end and by springs 24 and 24' at the other end. As shown by Fig. 2 the springs 16 and 16' are connected to the load-sustaining frame by pivot studs 17 and 17' respectively and are connected with the axle 11 by a coupling device 19 and pivot studs 18 and 18'. A saddle, indicated at 20 in Fig. 2, is affixed to the load-sustaining frame and has portions which rest respectively on the upper leaves of the springs 16 and 16'. The details of this saddle 20 are similar to those shown by Fig. 5, this figure, however, being related to the structure shown by Fig. 3 rather than to that shown by Fig. 2. The spring-engaging portions of the saddle included in Fig. 2 are similar to those indicated at 21 and 21' in Fig. 5. The parts 17, 17', and the saddle 20, or some structure having a like function, comprise the anchorage between the springs and the vehicle frame. With this anchorage no provision for taking up downward thrust or rebound is required, because of the action of the abutment or thrust member 22, which I locate on the frame, as hereinafter described.

The mounting of the springs 24 and 24' is, to all intents and purposes, the same as that of the springs 16 and 16'. As shown by Fig. 3 the springs 24 and 24' are connected to the load-sustaining frame by pivot studs 25 and 25' and are connected to the axle 10 by a coupling device 27 and pivot

studs 26 and 26'. The saddle 20 included in Fig. 3 and otherwise shown by Fig. 5 is affixed to the load-sustaining frame, and its portions 21 and 21' rest upon the upper leaves of the springs 24 and 24'.

The duplex spring arrangement shown by Figs. 2 and 3 is optional and is but one specific embodiment of this invention, as will be understood after further explanation. The feature of this invention which is embodied in each modification shown is the provision of means arranged to keep a portion of the spring structure deflected from its normal position and at the same time leave another portion free to vibrate. Figs. 2, 3 and 6 illustrate abutments 22 which are arranged to engage the springs for the purpose stated. These abutments are preferably composed of suitable soft material, such as rubber, in order to avoid noise due to rattling. The elements 22 are carried by brackets 23, which brackets are affixed to the load-sustaining frame. The dotted lines included in Figs. 2 and 3 indicate approximately the curvature which the springs would assume when supporting a relatively light load if the abutments 22 were omitted. These abutments keep the springs deflected from their normal position but do not prevent greater deflection due to an excessive load. For example, when the load upon the springs exceeds the force exerted on the springs by the abutments, the springs are freed from the abutments. The phrase "critical load" will be used to mean a load which is just sufficient to relieve the abutments 22 from the pressure of the springs, without separating the springs from the abutments. When the springs are supporting a load less than the critical load, a substantial portion of the spring length is not used. In this case the portion of the spring length which is free to vibrate includes (Fig. 2) the spring 16 and that portion of 16' which is between the abutment 22 and the axle 11, while of the structure shown by Fig. 3 the spring structure which is free to vibrate is the spring 24 and that portion of spring 24' which is between the abutment 22 and the axle 10. The portions which are not free to vibrate under the condition last named are that portion of spring 16' between the abutment 22 and saddle 20 and the corresponding portion of spring 24 in Fig. 3. From this explanation it may be seen that one effect of the abutments 22 is to prevent vibration of a portion of the spring length when the load is less than the critical load. In this connection it is to be observed that the relatively limber portions and not the relatively stiff portions of the spring structure are the ones which are free and active when supporting a load lighter than the critical load.

Fig. 8 shows a spring structure equivalent

in some particulars to that shown by Fig. 2, excepting that a single spring is shown instead of the duplex spring. In Fig. 8 the spring 16^x is connected to the load-sustaining frame 14 by a pivot stud 17^x, and is connected to a coupling device 19^x by a pivot stud 18^x. The hanger is carried by the axle 11. 20^x indicates a saddle which is affixed to the frame 14 and rests upon the top leaf of the spring. 22^x indicates an abutment which is, to all intents and purposes, equivalent to that hereinbefore described. This figure, however, shows the abutment 22^x mounted in such manner as to be adjustable to vary the initial deflection of the spring. For this purpose the abutment is provided with a screw stem 28 which is threaded in the bracket 23^x. The bracket is affixed to the frame 14. It will be noted that the form of my invention shown in Figs. 1 to 7 differs from Fig. 8 generally in that the upper spring 16 of the double arrangement superimposes its effect upon that of the lower spring and supplements the action of the latter for both light and heavy loads. It enables the individual springs to be made more flexible for the same load or enables a greater load to be carried on individual springs of a given size.

The invention is not limited to springs extending longitudinally of the vehicle. It should be noted, however, that where the springs extend longitudinally of the vehicle and are arranged as shown, the use of axle-carrying or axle-torsion rods, or other structures for performing like functions, is made unnecessary, since these functions are performed by my improved spring construction in addition to the spring functions.

The use of this invention affords marked advantages in the case of vehicles generally, and especially with automobiles when the road surface is irregular and the travel of the car is relatively rapid. The fact that the spring 16' or 16^x yields through only a portion of its length in response to small irregularities in the road tends to reduce the amplitude and shorten the period of the vertical oscillations acquired by the body. Under a load or impact exceeding the critical load the remaining length of the spring, back of abutment 22 or 22^x is automatically brought into action and gives a cushioning effect proportioned to the increased stress. The transition occurs without shock or any abrupt increase of spring resistance; and since both ends are then under a tension corresponding to this critical load, the spring is of course relatively stiff or resistant throughout its entire length. The amplitude of the upward movement of the body which follows this deflection is materially lessened by the reseating of said spring on its abutment, and it is an important advantage of my invention that it accom-

plishes this checking of the rebound without requiring the use of frictional shock-absorbers, snubbing straps or similar devices.

Looked at in another way, the outer section of the spring 16' or 16^x may be regarded as corresponding to a vehicle spring of ordinary length, while the inner section is a reverse portion which adds to the effective length and cushioning properties of such spring in order to take care of excessive loads and impacts, but which avoids the extreme rebound of the body experienced with an ordinary spring of corresponding total length.

15 The adjustment of the abutment 22^x provided in Fig. 8 enables the initial tension of the inner spring section to be regulated at will to correspond with the weight of the passengers or other load.

20 The use of a cantaliver or similar type of spring in connection with an abutment, such as 22, on the frame, having the functions mentioned, enables me to utilize and increase the well known easy-riding qualities of these springs without suffering the usual disadvantages of a relatively long spring, and at the same time it imposes the strain of initial deflection and rebound upon the frame, rather than upon the axle, and 25 avoids the necessity for any heavier construction of the axle or axle-attachment of the spring.

The difference in lengths between the free portions of the springs 16, 16',—that is to 30 say, the free portions of the spring 16 is that part between the pivot stud 18 and the saddle 20, while the free portion of the spring 16' when the latter rests on the abutment 22, is between said abutment and the 35 pivot stud 18,—is such that when the spring 16' is clear of the abutment 22, both springs 16, 16' will have the same amplitude of vibration; when, however, the abutment 22 engages the spring 16', the latter will then 40 have an amplitude or breadth of vibration less than that of the spring 16, with the result that the vibration of one spring counteracts that of the other. This feature of my 45 invention, while present in the duplex form shown in Figs. 2 and 3, for instance, would not be present in the single form shown in Fig. 8. In both forms of spring, however, the use of the abutment and the anchorage 50 provides means for applying initial deflection to the spring in such a way that the latter is free of the influence of the abutment under loads or shocks in excess of the predetermined weight selected in each particular case to give the desired permanent initial 55 deflection.

Having thus explained the nature of my invention and described a way of constructing and using the same, though without attempting to set forth all of the forms in 60 which it may be made, or all the modes of

its use, what I claim and desire to secure by Letters Patent is:—

1. In a vehicle, the combination with a frame and a wheel-axle, of a leaf spring having its inner portion anchored to the frame, 70 and its outer portion attached to the axle, and an abutment on the frame bearing against the under side of the spring intermediate of its anchorage and its outer end, and serving to hold the inner section of the 75 spring under a permanent initial deflection.

2. In a vehicle, the combination with a frame and a wheel-axle, of a leaf spring tapered at both ends, the outer end being attached to the axle and the inner end being 80 attached to the frame, and the intermediate portion of the spring bearing upwardly against the frame, and an abutment on the frame, normally bearing against the under side of the spring between the said upward-bearing point and the axle and serving to hold the inner section of the spring under permanent initial deflection, while permitting the spring to yield as a whole to loads in excess of that represented by the initial 85 deflection.

3. In a vehicle, the combination with a frame and axle, of two superimposed leaf springs anchored at their inner portions to the frame and attached to the axle at their 95 outer ends, one of said springs being normally free to vibrate throughout its length, and an abutment on the frame bearing against the under side of the other spring intermediate of its anchorage and its outer 100 end and serving to hold the inner section thereof under a permanent initial deflection.

4. In a vehicle, the combination with a frame and axle, of two superimposed leaf springs, the outer ends of said springs being attached to the axle, and the inner ends to the frame, and the intermediate portion bearing upwardly against the frame, and an abutment on the frame normally bearing against the under side of one of said springs 105 between the said upward bearing point and the axle, and serving to hold the inner portion thereof under a permanent initial deflection.

5. In a vehicle, the combination with a 115 frame and a wheel-axle, of two superimposed leaf springs, the outer ends of said springs being attached to the axle, and the inner ends to the frame, and means for subjecting the inner portion of one of said springs to a predetermined initial compression, said means being arranged to automatically release said action on said spring when said frame is subjected to loads or shocks in excess of said initial compression and to automatically establish and maintain said initial compression when said loads or shocks do not exceed said initial compression.

6. In a vehicle, the combination with a frame and a wheel-axle, of a leaf-spring 130

anchored on one of said members and having its free end attached to the other member, and an abutment on the first said member bearing against one side of the spring, intermediate of the anchorage and the free end of the latter, and serving as a stop to hold that portion between the anchorage and the abutment under a permanent initial deflection, the spring being free to flex under

maximum load throughout substantially its entire length between said anchorage and its free end.

In testimony whereof I have affixed my signature, in presence of two witnesses.

HERBERT H. BUFFUM.
